RACK FOR HANDLING CONTINUOUS FAN-FOLD FORMS

Boyd L. Miller and Robert E. Schaefer, Clinton, Iowa, assignors to Chamberlain Manufacturing Corporation, Elmhurst, Ill.

Filed June 15, 1970, Ser. No. 23,473

Term of patent 14 years

Int. Cl. D18—02

U.S. Cl. D64—11

FIG. 1

FIG. 1 is a front elevational view of our new design;
 FIG. 2 is a top plan view thereof; and

FIG. 3 is an elevational view of one side thereof, the
 opposite side being the same in mirror image.

We claim:

The ornamental design for a rack for handling continuous fan-fold forms, as shown and described.
